DESIGN FOR A PERFUME BOTTLE

Marcus Terbey, New York, N. Y.

Application May 10, 1937, Serial No. 69,283

Term of patent 7 years

To all whom it may concern:

Be it known that I, Marcus Terbey, a citizen of the United States, residing at 535 West 113th Street, New York city, in the county of New York and State of New York, have invented a new, original, and ornamental Design for Perfume Bottle, of which the following is a specification, reference being had to the accompanying drawing, forming part thereof.

The figure is a perspective view of a perfume bottle showing my new design. The sides of the bottle not shown in the drawing are substantially the same in appearance as the sides illustrated.

I claim:

The ornamental design for a perfume bottle as shown and described.

MARCUS TERBEY.
